(57) **CLAIM**

We claim the ornamental design for a digital camera, as shown and described.

DESCRIPTION

FIG. 1 is a front, left and top perspective view of a digital camera showing our new design;

FIG. 2 is a front-side elevational view thereof;

FIG. 3 is a rear-side elevational view thereof;

FIG. 4 is a left-side elevational view thereof;

FIG. 5 is a right-side elevational view thereof;

FIG. 6 is a top-side elevational view thereof; and,

FIG. 7 is a bottom-side elevational view thereof.

The broken lines depict portions of the camera in which the design is embodied that are not considered part of the claimed design.
